(57) **CLAIM**

The ornamental design for a cover for a boat stand plate, as shown and described.

DESCRIPTION

FIG. 1 is a top plan view for a cover for a boat stand showing a first embodiment of our design.

FIG. 2 is a section view of the cover cut along line 2-2 of FIG. 1, with the opposing view being a mirror image thereof.

FIG. 3 is a section view of the cover cut along line 3-3 of FIG. 1, with the opposing view being a mirror image thereof.

FIG. 4 is a top plan view for a cover for a boat stand showing a second embodiment of our design.

FIG. 5 is a section view of the cover cut along line 5-5 of FIG. 4, with the opposing view being mirror image thereof; and,

FIG. 6 is a section view of the cover cut along line 6-6 of FIG. 4, with the opposing view being mirror image thereof. The broken lines in the drawings show portions of the cover for a boat stand plate, which form no part of the claimed design.
